DEHYDRATOR

Filed Feb. 16, 1927

FIG. 1.

FIG. 2.

Inventor,
Victor L Gibson,
per McGrandall
Attorney.

UNITED STATES PATENT OFFICE.

VICTOR L. GIBSON, OF LOS ANGELES, CALIFORNIA.

DEHYDRATOR.

Application filed February 16, 1927. Serial No. 168,793.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to means for cleaning crude oil and other oils and freeing them from emulsions and mixtures of water. Among its more important objects are; first, to provide a dehydrator adapted to receive and purify crude oil as it comes from a well, and to operate anywhere as in close proximity to the well; second, to supply a dehydrator capable of removing water from oil emulsions without the use of chemicals or electrical devices; and, third, to accomplish the above by means of a relatively simple and inexpensive construction.

My objects are attained in the manner illustrated in the accompanying drawing, in which—

Figure 1 is a longitudinal section of the complete device in elevation, and

Figure 2 is a cross section of a portion of the device in plan view, the section being taken on the line 2—2 of Fig. 1.

Similar reference numerals refer to similar parts throughout both views.

My invention is based upon the material difference that exists between the specific gravities of oil, water, and emulsions of oil and water. It utilizes the principle of providing a multiplicity of deep riffles, or settling pockets, over which the unpurified oil is caused to flow. The mixture tends to segregate in the pockets, and the separated water and emulsion tends to collect in the bottoms thereof. I provide an automatic valve in each of these pockets adapted to trap away the water and emulsion that otherwise would accumulate therein, and thus only purified oil is discharged from the device.

An important feature of my dehydrator consists of causing the unpurified oil to flow

over the riffles in a thin, wide stream at a very low velocity. This makes it possible to utilize the natural segregating tendency to the fullest extent. Another feature consists of heating the unpurified oil and maintaining it at a uniform temperature during its passage over the riffles, irrespective of the velocity of flow, and thus obtain the maximum separating effect due to temperature. After passing through the dehydrator proper the hot oil is cooled in a manner to be described, before being discharged.

The embodiment of my invention selected for illustrative purposes comprises an upright shell 5 of rectangular section. Within this are stacked a plurality of slightly spaced rectangular riffle pans 6, one above the other, the pans being connected by vertical risers 7 in staggered arrangement. Between the pans are horizontal partitions 8 cooperating with the pans to form thin horizontal flow passages above them communicating with the risers. The pan riffles 9 are relatively deep as shown. They are arranged transversely to the flow and extend clear across the pans.

At the bottom of each riffle is an automatic valve 10 adapted to trap away water, or water and emulsion, as desired. The discharge orifices of these valves are connected to headers 11 leading into waste pipes 12. Such valves are readily procurable and do not constitute per se a part of my present invention. A suitable valve for this purpose is one that utilizes a float having a weight greater than the volume of oil that it displaces, but less than the weight of a corresponding volume of water, or of an emulsion of oil and water.

The riffle pans are smaller than the inside of shell 5, and are centrally arranged so as to provide a space 13 between them and the shell on all sides. A steam pipe 14 discharges into the shell at the bottom at 15, and the steam flows upwardly in spaces 13, and fills spaces 16 beneath the riffles, thus coming into direct contact with the whole of the under surfaces of the riffle pans, the upper surfaces of partitions 8, and the outer surfaces of risers 7. The steam after thus heating up the material

in the pans escapes from stack 17 at the top of the shell.

To maintain a uniform temperature in shell 5 during the purifying process I employ a suitable thermostat 18 penetrating into the material to be purified, and make use of a thermostatic valve 19 in the steam line, controlled by this thermostat. These devices are readily procurable and do not per se constitute a part of my present invention. I prefer to locate the thermostat about in the middle of the stack of riffle pans as shown.

The oil to be purified is led to the lowermost riffle pan through pipe 20. It may come from a pump, or directly from a pressure flow well through a gas trap as indicated at 21. In the latter event the gas trap is connected directly to the well through pipe 22, and the accumulated gas is discharged from the trap through pipe 23.

After passing over all of the riffle pans the purified hot oil passes out through passage 24, and thence downwardly through a series of thin, wide, horizontal, cooling chambers 25. These are arranged vertically one above the other in shell 26. The chambers are connected in staggered arrangement by vertical ducts 27, and are smaller than shell 26 so as to provide a space 28 all around. This shell has draft openings 29 at the bottom and a stack 30 at the top, thus providing for a natural draft of air which passes upwardly through the shell and comes in contact with all of the cooling surfaces.

35 A second cooling shell 31, with a similar arrangement of cooling chambers 32 receives the partially cooled oil discharged from duct 33, as indicated. This shell, like the other, has draft openings 34 and a stack 35. In 40 this shell the oil passes upwardly through its cooling chambers and its temperature is reduced to normal. The cool purified oil is then discharged through a duct 36 into a storage tank 37.

45 On account of temperature differences it often is desirable to space the shells slightly, or to introduce heat insulating material between them. Such material is not shown in the drawings but its use is contemplated by me when it appears to be necessary, and would at once occur to anyone having to do with the operation of such apparatus.

It will readily be seen that, by disposing my dehydrator in the flow line adjacent an 55 oil well, the oil will be dehydrated and cooled without vapor loss before going to storage. This effects a great saving in storage space and delivers the oil into storage free from water and ready for pipe line movement.

60 Having thus fully described my invention, I claim:

1. A dehydrator comprising; a vertical shell; a plurality of horizontal pans having deep transverse riffles, in spaced vertical arrangement within the shell; horizontal par-

titions between the pans forming flow passages above the pans; vertical ducts connecting said passages in series; and automatic valves at the bottoms of said riffles, adapted to open for the discharge of relatively heavy liquids, and to close for preventing the discharge of lighter liquids.

2. A dehydrator comprising; a vertical shell having an opening at the top; a steam pipe leading into the shell at the bottom; a plurality of horizontal pans having deep transverse riffles, in spaced vertical arrangement within the shell; horizontal partitions between the pans forming flow passages above the pans; vertical ducts connecting said passages in series; and automatic valves at the bottoms of said riffles, adapted to open for the discharge of water or emulsion of oil in water, and to close for preventing the discharge of oil.

3. A dehydrator comprising: a vertical shell having an opening at the top; a steam pipe leading into the shell at the bottom; a plurality of horizontal pans having deep transverse riffles, in spaced vertical arrangement within the shell; horizontal partitions between the pans forming flow passages above the pans; vertical ducts connecting said passages in series; automatic valves at the bottoms of said riffles, adapted to open for the discharge of water or emulsion of oil in water, and to close for preventing the discharge of oil; a thermostat intermediately placed in said flow passages; and a valve in said pipe adapted for actuation by said thermostat.

4. In a crude oil dehydrator having a series of housings for continuous treatment of a stream of oily liquid, an initial housing, a plurality of vertical shell like cooling housings having draft openings at the top and bottom thereof, a closed passageway leading continuously through said cooling housings and adapted to cool the stream of liquid delivered thereto from said initial housing, said passageway comprising a plurality of thin, wide, horizontal cooling chambers, vertical ducts connecting said cooling chambers in staggered arrangement, said cooling chambers being arranged in a superposed manner whereby the stream of oily liquid flows descendingly through one housing and ascendingly through the other, and a passage for the flow of the liquid from one housing to the other.

5. In a dehydrator, a dehydrating tower in combination with a plurality of cooling towers, said dehydrating tower compressing a vertical shell having an opening at the top; means for supplying a heating medium to said tower, a plurality of horizontal trays having deep transverse riffles in spaced vertical arrangement within the tower; horizontal partitions between the trays forming flow passages above the trays; vertical ducts connecting said passages in series; means for in-

- introducing oil and oil emulsions to be purified to the lowermost riffle tray, gravity means for separating the oil and water in said riffles as it is forced to flow upwardly over and across the several trays, automatic valves at the bottoms of said riffles adapted to open for the discharge of water or emulsion of oil in water and to close for preventing the discharge of oil, a passageway communicating with said dehydrator tower and said cooling towers and means for discharging from said dehydrator tower thereinto.
6. In apparatus of the character described a series of superposed substantially horizontal conduit sections, means affording communication between adjacent ends of said sections in order to embody the same in a continuous conduit, means for forcing a liquid upwardly through said conduit in a continuous stream and for heating said stream to a relatively high temperature in the lowest horizontal conduit and to a less degree of heat in the upper horizontal conduits, there being a series of enlargements formed in said horizontal conduits to retard the flow of liquids at such points, and drainage means in the bottom portions of said enlargements to remove from the liquid stream the heavier portions thereof.
- 30 7. A dehydrator comprising a zig-zag passage way provided with interruptions, means to conduct a liquid stream containing oil through said zig-zag passage way, whereby to vary the gravity of said liquid stream as it flows therethrough, a drainage duct leading from said interruptions, and automatic valves located in said interruptions and actuated according to the change in gravity of the liquid collecting therein.
- 40 8. In a crude oil dehydrator, a dehydrator tower, a zig-zag passage way leading through said tower and connecting with a liquid source of supply, regulatory means for heating said liquid as it passes through said dehydrator tower, said liquid being an emulsion of oil and water, said heating means providing a state of diaphoresis of said emulsion whereby to vary the emulsive content of said liquid as it flows therethrough, means in said passageway for segregating the moisture produced by said diaphoresis, and a plurality of automatic means for trapping away of said moisture as said liquid is segregated and flows through the passage way in said dehydrator tower.
- 50 9. In apparatus for segregating from each other mingled liquids of different specific gravities, a zig-zag passage having a substantially horizontal portion interrupted by a section of expanded cross sectional area to retard a current passing through said expanded section, a drainage outlet in the bottom portion of said expanded section, valves to control escape of the heavier liquids through said drainage outlet whereby to vary the gravity
- of the current flowing through said passage and means controlled automatically by the specific gravity of said liquid to operate said valves substantially as set forth.
10. In a crude oil dehydrator, the combination of a plurality of vertical shell like housings, certain of said housings comprising cooling housings having draft openings at the bottom and top thereof, a flow passage in said cooling housings connecting with a liquid source of supply, said flow passage comprising a series of thin, wide horizontal cooling chambers, vertical ducts connecting said cooling chambers in staggered arrangement and means for cooling the liquid in the flow passage as it flows slowly therethrough to a pipe line and thence onward to a place of storage.
- 15 11. In a dehydrator, a conduit adapted to have a liquid flow therethrough, said conduit comprising a series of pans, a series of interruptions in said pans, vertical ducts connecting said pans in series, means for heating said liquid, regulatory means for varying the temperature applied thereto, automatic valves in the bottom of said interruptions, said valves adapted to produce a regulatory purification of said liquid as it flows through said conduit.
- 20 12. In a dehydrator tower, a conduit formed of a series of riffle trays connective for liquid communication, means for conducting a liquid stream consisting of unpurified oil at a low velocity therethrough, means for heating and maintaining a constant temperature of said liquid during its passage over the riffles, said riffles being adapted to retard and segregate the water from the mixture, means to trap away the water thus segregated, whereby to vary the emulsion content and thereby to increasingly purify said liquid during the successive stages of its retardment therethrough and a discharge for the refined liquid.
- 25 13. In a dehydrator, a dehydrator tower, an ascending series of riffle pans, conduitly arranged to form a zig-zag passage way, means to introduce an unpurified liquid into said passage way, means to heat said liquid, recesses in said pans for retarding the flow of the liquid therethrough, means to vary the gravity of the liquid collecting in said recesses, said means being actuated according to the gravity of the liquid collecting therein, an intake in the bottom of said tower and discharging into said series of riffle pans and a duct in the top of said tower wherefrom to discharge said liquid after it has been purified in its passage, through said tower.
- 30 14. In a device of the class described, a vertical shell having an opening at the top, a gradational conduit comprising a plurality of superposed trays having deep transverse riffles for the transmission of a liquid emulsion, means to heat said liquid emulsion, reg-

ulatory means for varying the temperature applied thereto, said heat providing a state of diaphoresis of said liquid emulsion, said riffles being adapted to progressively segregate the moisture produced from said state of diaphoresis throughout the several gradations of said conduit, and automatic means to trap away the moisture thus segregated.
